UNITED STATES PATENT OFFICE.

SAMUEL KAYE, OF COLUMBUS, MISSISSIPPI.

BOTTLE-FILLING HEAD.

1,260,392.

Specification of Letters Patent. Patented Mar. 26, 1918.

Application filed July 12, 1913. Serial No. 778,715.

To all whom it may concern:

Be it known that I, SAMUEL KAYE, a citizen of the United States, residing at Columbus, in county of Lowndes and State 5 of Mississippi, have invented certain new and useful Improvements in Bottle-Filling Heads, of which the following is a specification.

My invention relates to an improvement 10 in bottling machines, and more particularly to an improvement in bottle-filling heads for such machines; and this present invention is an improvement on the invention disclosed in application filed by me January 15 28, 1908, Serial No. 412,994; and also has to do with mechanism which coöperates with the cap finger set forth in a pending application Serial No. 778,714, filed July 12, 1913.

In the accompanying drawings:—

Figure 1 is a view in side elevation of an improved head,

Fig. 2 is a vertical sectional view,

Fig. 3 is a view corresponding to Fig. 2 with parts in elevation and portions broken 25 away and showing the bottle projecting into the head and in the position of having the cap secured thereon.

Fig. 4 is a horizontal section on the line 4—4 of Fig. 2.

Figs. 5, 6, and 7 are horizontal sections on the line 5—5 of Fig. 2, showing the parts in different positions.

Fig. 8 is an enlarged vertical fragmentary section of the lower end of the filling-head, 35 and

Fig. 9 is a diagrammatic view illustrating the relation of parts of the bottling machine with respect to the filling head, which co-operate therewith to cause the automatic 40 and synchronous action of the parts of my invention.

A, represents the filling-head, which is, of course, only one of several in a completely-organized machine. This filling-head is 45 supported on a screw 1 which depends from a rod 2 from a point of support above on a circular track (not shown).

Within the head a receiving chamber 3 is formed. The size of this receiving chamber 50 may be varied, and the elevation of the head on the screw 1 may be regulated to suit the requirements of bottles of varying sizes by turning the screw 1 on the threads of the rod 2 and within the head A. After 55 this the lock-nut 4 is screwed in place, compressing the packing gasket 5 in the seat

6 in the upper end of the head, thus forming an air and water-tight joint at that point.

The filling-head A is supported on the 60 lower end of the rod 2, through the medium of screw 1 where it is held against turning by means of a strap 7, so that while the screw 1 is capable of being turned for raising and lowering the head to regulate the 65 size of chamber 3, the filling-head A and rod 2 are held together against axial turning.

Within the lower end of the head, the throat 8 is stationed. This throat has a flaring or conical mouth 9, into which the cap 70 C is forced by the cap-finger 10 from below, whereby the cap is held by the frictional engagement of its flaring edges against the wall of the throat.

In Fig. 2, the cap-finger is in the position 75 of receding from the filling-head, just after having forced the cap C into the throat 8.

One of the primary objects of my present invention is to prevent the leakage and waste of the liquid to be bottled. This necessitates a tight joint between the bottle-neck and the filling-head especially in the bottling of carbonated water or other effervescent liquids under pressure.

An elastic ring 12 is utilized for this purpose. This ring 12 is held at a point between the throat 8 and the mouth 11 of the filling-head, and through the orifice in the center of the elastic ring, the cap-finger 90 and the bottle-neck pass alternately.

Means is provided for compressing the elastic ring 12 around the bottle-neck, which comprises the compressors 13, 13, of which three are illustrated. These compressors are held slidably in the guide-cup 14 secured 95 on the lower end of the filling-head A by screws or other means 15, 15. The compressors 13, 13, move radially in this guide-cup, they being provided on their lower surfaces with radial tongues 16, which fit 100 and slide radially in the slots 17, in the bottom of the guide-cup 14. The outer surfaces 18 of the compressors 13 are correspondingly-curved eccentric to the center of the guide-cup in the form of cams and outside of each surface 18 is a groove 19.

A ring 21 is fitted and adapted to turn within the guide-cup 14. This ring is provided with as many depending lugs as there are compressors, and one lug is fitted to and 110 adapted to traverse each of the grooves 19, and to bear upon the corresponding cam

surface of a compressor, so that as the ring 21 is turned in one direction or the other, the lugs 20, 20, positively force the compressors 13, 13, radially in or out, and, when inwardly, uniform pressure is applied upon the elastic ring 12, thus causing it to tightly embrace the bottle-neck.

This pressure upon or compression of the elastic ring also forms a tight joint around 10 and against the bead 40 formed at the lower end of the filling-head proper. In this way the escape of air or liquid during the filling operation is made impossible.

As previously explained, the diameter of 15 the cap-finger 10 is greater than that of the bottle-neck. This condition is utilized for a purpose. While the natural tendency of the elastic ring 12 is to resume its normal proportions on the pressure of the compressors being removed, yet it is well understood that rubber sooner or later loses much 20 of its elasticity, especially when strain upon it is all in one direction. This is largely, if not wholly, overcome by repeatedly forcing 25 the cap-finger through the orifice in the center of the elastic ring and alternately with each outside compression of the ring, thus each time positively restoring the elastic ring to its normal proportions, in this way insuring 30 and preserving the normal proportions and dimensions of the elastic ring, thereby not only greatly prolonging its life but also getting the benefit of its highest efficiency during its life.

35 An outer band 22 fitted to turn on the lower end of the filling-head is secured to the ring 21 by studs 23, of which there are three shown in Fig. 5, these studs operating through elongated slots 24, 24, in the sides 40 of the cup 14.

The band 22 is provided with two arms 25 and 26 which extend out in more or less opposite directions, one in position to strike one of the main posts 27 of the machine, and 45 the other an obstruction 28 at predetermined intervals, one to turn the band 22 in a direction to compress the elastic ring 12 around the bottle-neck when the bottle is being filled, and the other to turn the band 50 to release the ring before the head is lifted from the bottle.

It is understood, of course, that the bottle-mouth is contracted around the neck of the bottle only when the bottle is being filled, 55 and not when the capping or removal of the bottle takes place.

The liquid to be bottled is supplied 60 through a fixed pipe 29, which extends downwardly alongside the filling-head, the lower end passing through a slot 31 in the band 22 into the head A at a point below the bottom of chamber 3. Through this bottom, the liquid discharges upwardly through the nozzle 30.

65 This pipe 29 is provided with a valve 32

which is normally closed by a spring 37 sleeved upon the stem of the valve. A head 33 on the end of this stem rests normally in the path of a lug 34 on the band 35 on the upper end of the filling-head.

70

After the bottle-neck has been forced through the orifice in the elastic ring, and the latter has been pressed tight around the neck, the band 35 is turned by the arm 36 thereon, striking an obstruction similar to 75 obstruction 28 which causes the lug 34 to engage head 33 on the valve stem and open the valve 32, whereupon the liquid from the carbonator (not shown) discharges into the receiving chamber 3, and after which the 80 parts are returned to normal by an obstruction similar to post 27, not shown.

An amount of liquid equal to the capacity 85 of the bottle being filled is discharged through the pipe 29 as determined by the size of the chamber 3. The pressure in the chamber and bottle become equalized, they 90 communicating through outlets 41 in the lower end of the filling-head A, and the supply of liquid to the bottle is thus automatically stopped, the liquid passing down through the outlets 41 into the bottle, and the air displaced from the bottle rising into the displacement and receiving chamber 3.

The displaced air from the bottle prevents 95 the accumulation of liquid in the chamber 3.

While the carbonator pressure is being maintained in the bottle, the cap is applied and secured to the bottle by the bead at the mouth of the bottle being forced beneath 100 the cap C into the throat 8, the tapering mouth 9 of which throat 8 thereby clenches the crimped edge of the cap around the beaded mouth of the bottle.

A rubber plug 38 in the throat 8 creates 105 sufficient pressure on the cap C to insure seating the cap properly, and as a result of its compression it forces the bottle free from the throat when the head lifts or rises from the bottle after the completion of the 110 capping operation.

Valve 32 remains open until the arm 36 on the band 35 leaves the obstruction, whereupon the spring 37 closes the valve 32. This is done previous to the filling-head being 115 removed from the bottle, and, by means of the upturned nozzle 30 of the supply pipe 29, the loss of the liquid remaining in that portion of the pipe below the valve (after the valve is shut) which would otherwise flow 120 out is prevented, it being one of the primary objects of my present invention, as previously stated, to prevent waste of any of the liquid to be bottled as well as leakage through the joint formed around the bottle-neck.

In this way I have provided simple but effective mechanism for the bottling of liquids by automatic machinery.

Having fully described my invention, what 130

I claim as new and desire to secure by Letters Patent, is:—

1. A bottle filling head having compressible means at the mouth thereof, through 5 which the neck of the bottle to be filled is inserted, means for automatically compressing said compressible means inwardly against the bottle to form a gas and watertight joint between the head and bottle, and 10 means of greater size than the neck of the bottle being capped adapted to pass through the compressible means.

2. A bottle filling head having compressible means at the mouth thereof through 15 which the neck of the bottle to be filled is inserted, means for automatically compressing said compressible means inwardly against the bottle to form a gas and watertight joint between the head and bottle, and 20 means of greater size than the neck of the bottle being capped adapted to pass through the compressible means for expanding the latter.

3. A bottle filling head having compressible means at the mouth thereof through 25 which the neck of the bottle to be filled is inserted, means for automatically compressing said compressible means inwardly against the bottle to form a gas and watertight joint between the head and bottle, and 30 means of greater size than the neck of the bottle being capped adapted to pass through the compressible means for expanding the latter alternately with each inward compression 35 of the compressible means.

4. In a bottling machine, the combination with a filling head having a mouth, an elastic ring adjacent to the mouth and having a central orifice which registers with the 40 mouth, of means for automatically applying inward pressure from without this ring to compress it around the neck of the bottle to be filled when the latter has been inserted through the mouth of the filling-head, and a 45 cap-finger of greater size than the bottle-neck, which is inserted through the mouth and the orifice of the elastic ring upon the removal of the outside pressure of the ring to expand the latter, said expansion and compression of the ring alternating with each other.

5. In a bottling machine, the combination with a filling-head having a receiving chamber therein, a supply-pipe leading thereto, 50 and a spring-actuated valve for the supply-pipe, of an elastic ring located at the mouth of the head through which the neck of the bottle to be filled is inserted, compressors and automatic means for forcing and hold-

ing the compressors inwardly against the 60 elastic ring preparatory to the filling of the bottle, and means for automatically opening the valve in the supply-pipe after the compression around the neck of the bottle shall have taken place, and for automatically closing 65 the valve in the supply-pipe to shut off the supply previous to the release of the compression on the elastic ring around the bottle-neck.

6. In a bottling machine, the combination 70 with a filling-head, a guide-cup secured at the lower end thereof having a central orifice therein which forms the mouth of the head, compressors radially movable on the bottom of the cup, an elastic ring held in position to 75 be compressed by said compressors around the neck of the bottle to be filled, said compressors having eccentric cam surfaces and grooves, a rotatable ring having lugs which traverse the cam surfaces and grooves, said rotatable ring 80 fitted to turn within the walls of the cup, a rotatable band surrounding the cup connected with the rotatable ring which carries the lugs which operate the compressors, and means for automatically turning said band 85 in one direction or the other to move the compressors in and out.

7. In a bottling machine, the combination 90 with a filling-head, a guide-cup secured at the lower end thereof having a central orifice therein which forms the throat of the head, compressors radially movable on the bottom of the cup, an elastic ring held in position to be compressed by said compressors around the neck of the bottle to be filled, said 95 compressors having eccentric cam surfaces and grooves, a rotatable ring having lugs which traverse the cam surfaces and grooves, said rotatable ring fitted to turn within the walls of the cup, a rotatable band surrounding 100 the cup connected with the rotatable ring which carries the lugs which operate the compressors, means for automatically turning said band in one direction or the other to move the compressors in and out, a liquid 105 supply pipe and a valve therein, and an upper band rotatably connected with the head having means thereon in position to engage the valve, and means for automatically turning the band to operate the 110 valve to control the supply of liquid to be discharged into the bottle.

In testimony whereof I affix my signature, in the presence of two witnesses.

SAMUEL KAYE.
